UNITED STATES PATENT OFFICE.

FREDERICK C. CARSTARPHEN, OF TRENTON, NEW JERSEY, ASSIGNOR TO THE AMERICAN STEEL AND WIRE COMPANY OF NEW JERSEY, OF HOBOKEN, NEW JERSEY, A CORPORATION OF NEW JERSEY.

GRIP FOR AERIAL TRAMWAYS.

1,218,372.

Specification of Letters Patent.

Patented Mar. 6, 1917.

Application filed May 31, 1916. Serial No. 100,870.

To all whom it may concern:

Be it known that I, FREDERICK C. CARSTARPHEN, a citizen of the United States, residing in Trenton, New Jersey, have invented 5 certain new and useful Improvements in Grips for Aerial Tramways, of which the following is a specification.

In aerial tramways there is a bucket or other load-supporting device carried by a 10 trolley which runs on a cable or rail and the trolley is moved by means of a traction cable which travels along adjacent to the track and is adapted to be gripped to the trolley to carry the latter or released to dump or 15 load the latter. The grip must be strong enough to fasten the trolley rigidly to the traction cable and must be easily attached and released; at the same time it has to be simple in order to operate successfully and 20 to be durable and reasonably cheap. On lines of considerable length it is customary to use several successive sections of traction cable. These cables are not always of exactly the same size, or if they are so in the 25 beginning they do not long maintain this relation. A grip which always closes to the same extent may be adjusted to hold satisfactorily on the larger diameter cable; but when it passes onto a section where a smaller 30 cable is installed, the grip will slip and permit the trolley and its load to run away. Or if the grip be adjusted to hold satisfactorily on the smaller cable it will not close properly on the larger one. The grip of the 35 present invention obviates this difficulty by compensating automatically for the ordinary variations in diameter of the different sections of a line.

The jaws of the grip should open upward 40 for the ordinary case where the traction line slopes downward in leaving a station; but where the line slopes upward the cable can be more readily gripped if its jaws are turned downward. I have provided a grip 45 which is universal in this respect, that it can be inverted and by a slight readjustment of the parts made to work as a bottom-opening grip.

Various other features of improvement 50 are referred to in detail hereinafter.

The accompanying drawings illustrate 55 embodiments of the invention.

Figure 1 is a rear face elevation showing

the grip and the adjacent part of the trolley in which it is mounted;

55

Fig. 2 is a face elevation of the same;

Fig. 3 is a side elevation of the grip separated from the trolley;

Fig. 4 is a section approximately on the line 4—4 of Fig. 1, illustrating the jaw-operating mechanism;

Fig. 5 is a similar view showing the readjustment of the parts to convert the grip to a bottom opening style.

Referring to the embodiment of the invention illustrated the gripping mechanism is mounted in a circular casing A surrounded by an annular groove which embraces the divided bearing ring B, C which constitutes or which is a part of the trolley. The 60 grip is thus adapted to turn about its axis to adapt itself to the inclination of the traction cable. As shown in Fig. 2, the traction cable D when it is gripped or seated in the jaw opening, bears on the guide rollers E so 65 that the grip casing will be turned about its axis (if necessary) to bring the jaw opening properly in line with the cable.

There is a fixed jaw F which is fastened in a suitable recess in the cast frame of the 70 grip. This fixed or back jaw may be made thicker or thinner or may be moved outward or inward by means of liners of different thicknesses behind it so as to make a coarse adjustment for different sizes of cable. The 75 outer jaw G is movable, being mounted on a pivot pin H and having a rearwardly extending operating arm J which is connected by a pin K with the upper ends of a pair of curved links L which at their lower ends are 80 pivotally connected through a pin M with the base portion N of an operating lever O. The operating lever pivots about a pin P with a toggle action. In the downward position of the lever O shown in full lines the 85 toggle is swung slightly past its center to pull down the pin M and the links L and to lock them, thus closing the movable jaw 90 and locking it on the cable.

In the course of the downward movement 100 of the lever O the movable jaw will engage the cable and after a slight compression will be prevented from moving farther inward. When this occurs the lever O, pivoting around the pin P cannot pull the pin M 105 down any farther, since it is connected with

the links L which in turn are connected to the movable jaw. In order to permit the completion of the toggle action therefore under these circumstances the pin P is arranged to yield upward, being mounted in the fork of a double bell crank lever having a pair of arms Q carrying said pin P and having an upwardly extending pair of arms R which engage a block S and bear against a strong coiled spring T; the bell crank lever being mounted in a pivot pin U which is fixed in the casing of the grip. The resistance of the spring T to compression measures the gripping pressure which is applied to the cable and also the closing pressure required on the end of the operating lever O. The grip is designed so that a spring T may be used of moderate strength and reasonable proportions and the ratios of leverage of the other operating parts are such that the gripping pressure is adequate for the purpose.

The extent of compression of the spring T is adjustable by means of a bolt V screwing into a squared nut V' which lies within a squared recess W in the front wall of the casing, the bolt head being supported by a bridge piece X mounted on the back of the casing. The downward motion of the bell crank lever Q, R is limited by the shoulder Y formed in the rear wall of the casing. The head of the bolt V forms a stop or buffer for the blow of the lever O when the latter is thrown upward in the act of detaching the grip, the lever being provided with a boss Z which strikes squarely against the head of the bolt, as indicated in dotted lines in Fig. 3. This bolt V can be replaced at a very slight cost if broken, without disturbing the assembly of the other parts.

When the operating lever O is in the open position it should be held there. This is accomplished by means of a flat spring a which presses against the underside of the arm J of the movable jaw. The spring a bears against the fulcrum formed by the knob b on the bell crank or compensating lever Q, R, and the pressure on the end of the spring is subject to adjustment by means of the screw c screwing through the front wall of the casing and provided with a lock nut d.

In the above description I have assumed that the pin P is fixed in the double arm Q of the bell crank or compensating lever. Preferably, however, this pivot pin is adjustably mounted in the manner indicated in Figs. 1 and 3. Each half of the double arm Q is finished as a bearing e with a slot 60 in which the pin P is adjustable vertically; each bearing being provided with upper and lower adjusting screws f and set nuts g, the adjusting screws bearing at opposite sides on the pin P so as to raise or lower the latter and hold it firmly in the position of ad-

justment. When the pin is raised the end of the closing lever is also raised, thus increasing the opening between the jaws; and when the pin P is lowered there is a corresponding reduction of the opening between the 70 jaws. This gives a fine adjustment in addition to the coarse adjustment of the back jaw F above referred to.

It will be noted that the center of the traction cable when gripped coincides with 75 the axis of the rotatable casing of the grip. Accordingly if the grip be rotated 180° all the parts will have the same relationship with the traction cable except that they will be inverted. The jaw will open downward 80 and will thus be in the best position to grip a traction cable which slopes upward from the station. The attaching and detaching of the grip is usually accomplished automatically by means of fixed inclined planes 85 striking the end of the operating lever O, the planes being inclined upward to unlock and downward to lock the grip. The herein described grip could be used for a bottom opening grip by suitably modifying the 90 planes which actuate the operating lever. Furthermore the present grip may be by a slight readjustment of the parts made to work in the inverted position with the same inclined detaching and attaching planes 95 which are used in the top opening position of the grip. For this purpose the operating lever is arranged to be inverted so that though the entire grip may be rotated about 180° on its axis the operating lever will still project downward in the closing position and upward in the open position of the jaws.

For this purpose it is only necessary to invert the lever O as shown in Fig. 5. Here the yielding pivot of the lever O is the pin 105 M (instead of the pin P as before), the pin M being mounted in the bearings e on the double arm Q of the compensating bell crank Q, R. At the same time the links L must be moved to the inner side of the pivot pins K and P so that they lie between these pins and the rear of the casing. With the parts in this position the action of the grip is the same as before, the throwing down of the operating lever O swings the toggle 110 links L upward to close the movable jaw G and when this can move no farther against the cable D then the bell crank lever will yield and permit a downward movement of the pivot pin M so as to allow the toggle to 115 swing past its dead center and lock. On throwing up the operating lever O the toggle links L will be lowered and the jaw opened.

Though I have described with great particularity of detail a certain specific embodiment of my invention yet it is not to be understood therefrom that the invention is restricted to the specific embodiment disclosed. Various modifications thereof in 120 125 130

detail and in the arrangement of the parts may be made by those skilled in the art without departing from the invention.

What I claim is—

5. 1. A grip for cableways adapted to be inverted so as to act either as a top opening or a bottom opening grip, said grip including an operating lever which is adapted to be inverted with relation to the remaining parts, 10 so that it may lie in the same direction for either the top opening or the bottom opening position of the grip.

2. A grip for cableways comprising a casing carrying gripping jaws and operating 15 mechanism therefor, said casing being rotatable about a transverse axis, said mechanism including an operating lever which is adapted to be inverted with relation to the remaining parts so that it may lie in the 20 same direction for either the upright or the inverted position of the casing.

3. A grip for cableways comprising a casing carrying gripping jaws and operating mechanism therefor, said casing being rotatable about a transverse axis, said mechanism including an arm connected to a movable one of said jaws, a link pivoted to the end of said arm, an operating lever pivoted to the opposite end of said link and pivotally 30 mounted at another point so as to form with said link a toggle for operating said movable jaw, said operating lever and link being adapted to be inverted with relation to the remaining parts so that the link may lie 35 in the same direction to grip the cable in either the upright or the inverted position of the casing.

4. A grip for cableways including in combination a movable jaw and an operating 40 lever for said jaw, said operating lever being pivotally mounted on a floating pivot

and being adapted to positively move said gripping jaw into and out of cable gripping position.

5. A grip for cableways including in combination a movable jaw, and an operating lever therefor mounted on a floating pivot, and a spring pressing said pivot in a direction to close the jaw.

6. A grip for cableways including in combination a movable jaw, a toggle mechanism for operating the same and a spring pressing the pivot of said toggle mechanism in a direction to close the jaw, and adapted to yield to permit a completion of the toggle action 55 when the movement of the jaw is stopped by the cable.

7. A grip for cableways including in combination a movable jaw, an operating arm therefor extending transversely, means engaging the rear end of said arm to actuate the jaw, a spring also extending transversely and means for transmitting the pressure of said spring to said jaw actuating means.

8. A grip for cableways including in combination a movable jaw, an arm thereof extending transversely to the rear of the grip, toggle mechanism engaging said arm to operate the jaw, a bell crank lever carrying the pivot of said toggle mechanism at the end of 70 one arm and a spring engaging the opposite arm and pressing said bell crank lever in a direction to cause the closing of the jaw.

9. A grip for cableways including in combination a pivoted lever having a movable 75 cable gripping jaw on one end, a floating pivot and an operating lever for said pivoted lever, said operating lever being pivotally mounted on said floating pivot.

In witness whereof, I have hereunto signed 80 my name.

FREDERICK C. CARSTARPHEN.
